UNITED STATES PATENT OFFICE.

WILLIAM O. MCCLINTOCK, OF WALNUT, CALIFORNIA.

HEAT DISTRIBUTOR FOR ORCHARD BURNERS.

Application filed December 29, 1922. Serial No. 309,718.

To all whom it may concern:

Be it known that I, WILLIAM O. MCCLINTOCK, a citizen of the United States, residing at Walnut, in the county of Los Angeles and State of California, have invented new and useful Improvements in Heat Distributors for Orchard Burners, of which the following is a specification.

This invention relates to apparatus for aiding in the prevention of frost in orange groves, and more particularly to devices of the kind known as orchard heaters comprising an oil pot having an upstanding stack through which the gases of combustion pass. It is an object of the invention to provide means for more generally distributing the heat produced by combustion of the fuel in the oil pot. Another object is to provide a distributor which, when in use, is adapted to be readily adjusted across the top of the usual smoke stack or flue of the heater and which, when out of use, is adapted to be disposed around the stack for compact storage and convenient disposition.

Other objects and advantages will be made manifest in the following specification of an embodiment of the invention illustrated in the accompanying drawings, wherein—

Figure 1 is a side elevation of a conventional form of orchard heater showing the distributor applied to the top of the stack, parts being in elevation.

Fig. 2 is a side elevation showing the distributor arranged, out of use, about the stack.

Fig. 3 is an underneath plan view of the distributor.

It is the very extensive practice to arrange orchard heaters of the type herein referred to at suitable points in the spaces between rows of trees, and during the operation of these heaters the products of combustion naturally rise in an unobstructed vertical column with a very inefficient distribution of the heat coming from the stack. It has been proposed to use small size heaters and to increase the number of the same so as to thereby gain the advantage of a more general distribution of the heat produced by the burning of the oil fuel. My present invention has for its broad object to provide means

for practically accomplishing a distribution of heat from one orchard heater that will be the equivalent of the use of a plurality of smaller heaters. Also my distributor is so constructed that during the burning of the fuel, the products of combustion are not only diverted laterally from the stack of the heater toward a plurality of outlets remote from the axis of the stack, but moreover my distributor provides for the downward radiation of a portion of the heat so as to accomplish a noticeable heating of the air around the stack and also to tend to heat the ground around the heater.

A conventional form of orchard heater is here shown as including an oil holding vessel or pot 2 from the top of which extends upwardly the usual smoke and flue stack 3 which is open at its top end.

The device of the present invention consists of an approximately cylindrical section of tubing 5 adapted to be arranged transversely upon the top of the stack 3; one side of the section of tubing being apertured or recessed as at 6 to snugly fit the top end of the stack. Preferably, the section 5 is longitudinally split as at 7 and has a diameter approximating the diameter of the stack 3.

It will be seen, therefore, that when it is desired to laterally divert the products of combustion from the heater, the distributor section 5 can be attached to the top of the stack 3, as clearly shown in Fig. 1; the distributor ends projecting in substantially equal distances on each side of the top of the stack to secure an approximately equal distribution of combustion products.

When the heater is out of use, the distributor 5 can be telescoped down around the stack 3, as clearly shown in Fig. 2, and thus is not only conveniently disposed and associated with the heater but also is arranged so as to occupy but little additional space in storage and in field.

Further embodiments, modifications and changes may be resorted to within the spirit of the invention as here claimed.

What is claimed is:

1. A heat distributor for orchard heaters having smoke stacks, said distributor consisting of a substantially tubular longitudi-

nally split member having an opening at one side to receive the upper end of the said smoke stack.

2. A heat distributor for orchard heaters having smoke stacks, said distributor consisting of a substantially tubular member having an opening at one side to receive the

upper end of the said smoke stack, and also being longitudinally split so that it may be telescoped about the stack.

In testimony whereof I have signed my name to this specification.

W. O. McCLINTOCK.
